VANITY DESK

Ernest Herrmann, Hillsdale, N. J., assignor to Heywood-Wakefield Company, Gardner, Mass., a corporation of Massachusetts

Application December 14, 1954, Serial No. 33,561

Term of patent 7 years

(Cl. D33—7)

Fig. 2.

Fig. 1.

Fig. 3.

Fig. 4.

Fig. 1 is a front perspective view of a vanity desk showing my new design,

Fig. 2 is a top plan view of the vanity desk,

Fig. 3 is an enlarged fragmentary view along the line 3—3 of Fig. 1, partly in section and partly in perspective, and

Fig. 4 is an enlarged perspective view of one of the handle elements.

The stippling on the handle elements indicates contrast.

I claim:

The ornamental design for a vanity desk, substantially as shown and described.
